SLIVER ROLL FORMING MACHINE

Gordon Fraser, Norman Fraser, and John Fraser,
Arbroath, Angus, ScotlandApplication December 21, 1933, Serial No. 703,474
In Great Britain December 28, 1932

8 Claims. (Cl. 19—158)

This invention relates to sliver roll-forming machines of the type in which the sliver rolls are built upon a sectional arbor between a pair of pivoted cheek plates under the action of a frictional pressure roller positioned between the cheek plates.

The sectional arbor comprises a pair of arbor sections each retractable endwise, and carried one by each cheek plate.

10 The cheek plates are relatively fixed and are arranged to swing about a horizontal axis remote from the sectional arbor, being preferably pivoted on a fixed horizontal shaft.

During roll-building the cheek plates rise in 15 opposition to frictional restraint under the control of an operative, whereby to impart the requisite pressure to the roll.

According to the invention, for exercising frictional restraint on the movement of the cheek 20 plates there are provided a segment member concentric with the pivotal axis of the cheek plates and at least one friction member engageable with said segment member, one of said members being fixed and the other movable with the cheek plates.

25 A sliver roll-forming machine constructed in accordance with the present invention is illustrated in the accompanying drawings in which Figs. 1 and 1a together constitute a side elevation, Fig. 2 a fragmentary section on the line 30 a—a of Fig. 1 drawn to a larger scale, and Fig. 3 a fragmentary elevation showing differential sliver guide-traversing mechanism.

The sliver roll-forming machine shown comprises a horizontally spaced pair of cheek plates 35 1 of general triangular shape in elevation mounted to perform pivotal rising and falling movements about the axis of a fixed horizontal shaft 2 extending transversely of the cheek plates and penetrating one corner of each cheek plate 1.

40 3 denotes a tubular distance piece surrounding the shaft 2 and serving rigidly to interconnect the cheek plates 1 in spaced relation.

Sliver rolls are built up between the cheek plates 1 on axially movable rotatable arbor sections 4, 4^a mounted in coaxial relation in the cheek plates 1, under the action of a frictional pressure roller 5 rotatable between the cheek plates 1 and secured on a main drive shaft 6 disposed below and parallel with the shaft 2.

45 50 Each arbor section 4 or 4^a is hollow and is rotatably mounted on ball bearings 7 mounted on a stud shaft 8 carried by a sleeve 9 rotatably and axially movable in a boss 10 of the respective cheek plate 1. Each sleeve 9 is formed with a 55 peripheral cam groove 11 into which projects the

tail 12 of a pin 13 screw-threaded radially into the boss 10, the arrangement being such that rotational movement of the sleeve 9 within the limits defined by the ends of the slot 11 is accompanied by axial displacement of the sleeve 9 and of the respective arbor sections 4, 4^a, effecting retraction of the arbor sections 4, 4^a to an extent sufficient to permit ejection of a completed sliver roll from between the cheek plates 1.

55 The cam grooves 11 are provided with dwell portions which ensure that the arbor sections 4, 4^a are securely held in operative position during roll-building.

The two arbor sections 4, 4^a are adapted to be advanced and withdrawn simultaneously, being 10 operatively interconnected by means including arms 14, 14^a, respectively, attached one to the outer end of each sleeve 9, links 15, 15^a connecting the arms 14, 14^a to arms 16, 16^a secured on opposite ends of a rock shaft 17 journalled in bearings in the cheek plates 1. The arm 14 which is disposed to the left of an operative standing in front of and facing the machine is extended to present a manually operable lever 18 adapted to be rocked in the directions indicated by the 15 arrows A and B (Fig. 1) whereby to effect withdrawal and advance, respectively, of the arbor sections 4, 4^a.

20 As is understood, when starting-up, the cheek plates 1 are in their lowermost position with the arbor sections 4, 4^a resting on, and frictionally driven by, the pressure roller 5, so that sliver entrained by the arbor sections is built up thereon under the action of the pressure roller 5, the 25 arbor sections and cheek plates rising as the roll-building operation progresses.

30 35 40 45 50 55 To impart the requisite building-up pressure to the sliver roll, restraint is exercised by the operative against the rising movement of the cheek plates 1 by means including opposed arcuate friction pads 19, 20 carried by the cheek plate 1 seen in Fig. 1 and frictionally engaging opposed arcuate faces presented by a fixed segment 21 concentric with the shaft 2 and anchored to the adjacent side gable 22 of the machine. The friction pads 19, 20 are attached to shoes 19^a, 20^a slidably guided in the cheek plate between guides 20^b, 20^b for movement radially of the shaft 2 and embraced by a yoke 23 including two side plates straddling the shoes and carrying pins 24, 25 which act on the shoes 19^a, 20^a, respectively. The pin 24 is screw-threaded through the pivoted end of a lever 26 pivoted at 27 to the front end of the yoke 23. The pin 24 constitutes a toggle element and its inner end engages a recess in the shoe 19^a.

presenting a cam face 28 engageable by said inner end of the pin 24. As will readily be understood, the arrangement is such that downward effort exercised by the operative on the lever 26 during roll-building will cause the inner end of the pin 24 forcibly to engage the cam face 28 and press the shoes 19^a, 20^a towards one another and the pads 19, 20 thereon into frictional engagement with the segment 21 and thus provide the requisite drag against the ascent of the cheek plates and arbor sections. The weight of the lever 26 exerts sufficient frictional restraint on the segment 21 to prevent descent of the cheek plates when the lever 26 is released by the operative on completion of the sliver roll.

Ejection of a completed roll indicated at 29 and re-starting of the machine are effected by withdrawing the arbor-sections 4, 4^a by manipulation of the lever 18, removing the roll 29 from between the cheek plates 1 to a roll-supporting bar 30 located in front of the pressure roller 5, restoring the arbor sections 4, 4^a to operative position, permitting the cheek plates to descend until the arbor sections contact with the pressure roller 5 and nip the sliver end, removing the completed sliver roll 29 to break the sliver end, and wrapping said sliver end around the arbor sections 4, 4^a for a re-start.

To permit the cheek plates to be raised or lowered manually in any contingency, handles 47

30 carried by a horizontal tube 32 engageable by a fender-cam 33 unitary with the cheek plate structure. To impart traverse movements to the sliver guide 31, the tube 32 is adapted to be reciprocated endwise by means of differential driving mechanism (Fig. 3) including a rotary driving disc 34 frictionally engaged by a friction wheel 35 disposed at right angles to the disc 34 and feathered on a shaft 36 for movement radially of the disc 34 under the control of a cam 37 moving with the cheek plate structure. The cam 37 effects translatory movements of the wheel 35 through the medium of a bell-crank lever pivoted at 38, one arm 39 of said lever being provided with a follower 40 engageable by the cam 37 and the other arm 41 of said lever being operatively connected to the wheel 35. Secured on one end of the shaft 36 is a disc 42 carrying a crank pin 43 which, in the rotation of the shaft 36, imparts reciprocatory motion to a spindle 44 slidably mounted at the rear of the side gables 50 of the machine, the crank pin 43 being operatively connected to one end of the spindle 44 by means of a link 45. The reciprocatory motion of the spindle 44 is transmitted to the sliver guide-carrying tube 32 by means of a bar 46 the upper 60 end of which is rigidly attached to the tube 32 and the lower end of which is pivotally connected to the spindle 44 by the pin 46' in such wise that, while the bar 46 is free to pivot about the axis of the spindle 44, it is constrained to transmit the reciprocatory motion of the spindle 44 to the tube 32. The bar 46 being swingable about the axis of the spindle 44, the sliver guide 31 is disposed closely adjacent to the arbor sections 4, 4^a when starting up and closely adjacent to the periphery 70 of the roll throughout the roll-building operation, being prevented by the fender-cam 33 from actually contacting with the periphery of the roll.

It has been found that, if flat sliver be reciprocated at a constant speed, it tends to superim-

pose itself at one or more diameters of the roll, resulting in badly formed rolls. To avoid this drawback, the tube 32 is reciprocated by a differential driving mechanism.

In the particular arrangement illustrated a drawing frame of which one end gable is indicated at 48 serves slivers 49 to a plurality of roll-forming machines arranged in parallel, the shafts 2 and 6, the bar 30, the traverse spindle 44, and the differential guide-traversing mechanism (Fig. 3) being common to all the roll-forming machines.

The main drive shaft 6 is driven from the drawing frame through sprocket-chain drives 50, 51 between which is interposed a change-speed gear train indicated generally at 52 and including spur wheels which are changeable to compensate for variation of speed at the drive, take-off, or draft change, on the drawing frame or for draft change within the roll-forming machines.

53 denotes the handle of the drawing frame driving belt set-off mechanism.

We claim:—

1. A sliver roll-forming machine comprising a pair of spaced relatively fixed cheek plates 25 mounted for joint pivotal movement on a horizontal axis, shoes carried by one of said cheek plates, pads of friction material attached to said shoes, a yoke interconnecting said shoes, a frictional pressure roller positioned between said cheek plates, a coaxial pair of arbor sections carried one by each cheek plate and retractable endwise to permit ejection of a completed roll from between said cheek plates, a fixed segment 35 concentric with said axis, said segment member presenting opposed arcuate faces, and a lever pivotally connected to said yoke and manually operable to force said pads into frictional engagement with said segment.

2. A sliver roll-forming machine as claimed in claim 1 in which each arbor section is carried by a sleeve formed with a cam groove engaged by a fixed pin and so shaped that rotational movement of the sleeve effects axial displacement of the arbor section.

3. A sliver roll-forming machine as claimed in claim 1 in which the arbor sections are interconnected by crank and connecting rod mechanism for simultaneous operation.

4. A sliver roll-forming machine as claimed in claim 1 including a sliver-traversing guide adapted to be reciprocated by differential drive mechanism controlled by a cam moving with the cheek plates.

5. A sliver roll-forming machine as claimed in claim 1 incorporating a sliver guide and differential mechanism for reciprocating the sliver guide, said mechanism comprising a rotary driving disc, a friction wheel disposed at right angles to said disc and in frictional contact therewith, 60 said wheel being mounted on a shaft for movement radially of said disc under the control of a cam moving with the cheek plates, and a crank driven by said shaft for imparting endwise reciprocatory movement to a spindle operatively connected to the guide.

6. A sliver roll-forming machine as claimed in claim 1 incorporating a sliver guide secured on a horizontal tube or rod operatively connected to a reciprocatory spindle by means of a bar arranged 70 for circular movement about the axis of said spindle.

7. A sliver roll-forming machine as claimed in claim 1 incorporating a sliver guide and a fender-cam moving with the cheek plates and adapted to 75

maintain the sliver guide closely adjacent to but out of actual contact with the roll throughout the roll-building operation.

8. A sliver-roll-forming machine comprising a pair of spaced fixed cheek plates mounted for pivotal movement on a horizontal axis, a frictional pressure roller positioned between said cheek plates, a coaxial pair of endwise retractable arbor sections carried one by each cheek plate, a fixed arcuate segment concentric with said axis, and friction members engageable with said arcu-

ate segment for exercising frictional resistance to movement of said cheek plates about said axis, a yoke straddling said friction members, a lever pivoted to said yoke, and a pin carried by said lever and engaged with one of said friction members, said pin being manually operable to effect frictional engagement of said friction members with said segment. 5
